C. FREDERICK.
FOUNTAIN BRUSH.
APPLICATION FILED OCT. 7, 1915.

1,188,262.

Patented June 20, 1916

UNITED STATES PATENT OFFICE.

CLAUDE FREDERICK, OF SALISBURY, NORTH CAROLINA.

FOUNTAIN-BRUSH.

1,188,262.

Specification of Letters Patent. Patented June 20, 1916.

Application filed October 7, 1915. Serial No. 54,585.

To all whom it may concern:

Be it known that I, CLAUDE FREDERICK, a citizen of the United States, and a resident of Salisbury, in the county of Rowan 5 and State of North Carolina, have invented a certain new and useful Improvement in Fountain-Brushes, of which the following is a specification.

My invention relates to improvements in 10 fountain brushes for use in cleaning vehicle bodies, walls, etc., and it consists in the combinations, constructions, and arrangements herein described and claimed.

An object of my invention is to provide 15 a fountain brush or mop having a back which is perforated to permit the entrance of a stream of water, and which is provided with means for detachably holding the strands of the brush or mop.

20 A further object of my invention is to provide a device the type described in which the strands are held by spring means to the back in such a manner that while the holding means will prevent accidental displacement of the strands or their detachment 25 from the head, the strands may be detached when it is desirable to change them for a new set.

20 A further object of my invention is to provide a fountain mop of the type described in which the strands are arranged in a circle, these strands being bound with canvas or other suitable flexible reinforcing strips and being held in position on the 35 back by means of a spring which runs through the assembled strands and their reinforcing strips.

30 A further object of my invention is to provide a device of the type described in which the mop may be detached and a brush substituted.

Other objects and advantages will appear 45 in the following specification, and the novel features of the invention will be particularly pointed out in the appended claims.

My invention is illustrated in the accompanying drawings forming part of this application, in which—

Figure 1 is a perspective view of the device. Fig. 2 is a section through the back and the means for retaining the strands to the back. Fig. 3 is a section along the line 3—3 of Fig. 2. Fig. 4 is a section along the line 4—4 of Fig. 1, and Fig. 5 is a section through a modified form of the device.

In carrying out my invention I provide a

head 1, see Fig. 2. This head is of a substantially circular shape. It is provided with a circumferential groove 2. An integral plate 1^a is provided with a recess 1^b 60 for the insertion of a metal disk or plate 3, this metal disk or plate 3 being preferably made of some metal like brass, while the member 1 is preferably made of aluminum. The plate 1^a is provided with a central opening 1^c arranged to receive the reduced portion 4^a of a screw plug 4 which is threaded into a central opening into the plate 3. The pipe portion 4^a is provided with perforations 4^b. As will be seen from Fig. 2, these 70 perforations extend in such a direction as to throw the water onto the strands 5. The plate 3 may be secured to the portion 1^a by means of screws 6 or in any suitable manner. The screw plug 4 is threaded to receive an elbow 7 which in turn connects with a pipe 8 having a valve 9. A handle 10 is disposed near the valve 9 and another handle 11 near the end of the pipe 8. A flexible connection 12 leads to a source of 80 water supply 13.

In Fig. 2 I have shown the preferred form of the mop. In this figure it will be observed that a circular coiled spring 14 is provided around which is placed an interior reinforcing strip 15 of canvas or the like, while over the reinforcing strip 15 are doubled the strands 5. An outer reinforcing strip 17 is then formed and the inner and outer reinforcing strips, together with 90 the strands inclosed, may be stitched along the line 18 so as to prevent the displacement of the spiral spring 14.

From the foregoing description of the various parts of the device, the operation 95 thereof may be readily understood.

When the strands of the brush or mop are secured together around the spring 14, these strands form a circular body having a ring-shaped top. All that is necessary is to force 100 the back 1 down into the center of this ring. Owing to the resilience of the spring 14, the latter will stretch, so that when the parts are in the position shown in Fig. 2, the outer canvas reinforcement will enter the groove 2 and the strands will be held fixedly in this position by means of the spring 14. The water may be turned on at 9, and entering through the pipe 8, plug 4, extension 4^a and perforations 4^b will be supplied to the 110 strands 5, so that in washing vehicle bodies, such as automobile bodies, a continuous flow

may be kept up, washing away any grit and thereby obviating any tendency to scratch the surface of the vehicle.

When it is desired to change the strands, 5 the back 1 may be pulled out of the assembled strands, the spring 14 giving and thus permitting the back to be disengaged. A new set of strands may be applied, or a bristle brush be substituted. In Fig. 5 I have 10 shown such a brush. In this figure, a plate 3 is secured by means of screws 6 to a back 20. Bristles 21 are carried by the back and the latter is provided with a peripheral groove 22 arranged to receive a resilient 15 buffer 23 of rubber or other suitable material. The back 20 is provided with a central opening 23 corresponding to the opening 1^c in Fig. 2, and the pipe 4^a is arranged to project through this central opening. In 20 this form of the device, it is only necessary to screw it to the plug 4 in lieu of the mop assembly when the same handle and intake pipe may be used. The rubber buffer 23 is 25 for the purpose of preventing breakage of windows, when washing windows, or of marring the varnish or other easily damaged parts.

It will be noted that the resilient body 30 formed by the mass of strands 5 held by the reinforcing members 15 and 17, forms a buffer which prevents breakage or marring, in the use of the device.

I claim:—

1. In a fountain brush or mop, a back of 35 circular shape having a central opening and a peripheral groove, means extending through said central opening for delivering water, a plurality of strands secured together and having a portion arranged to extend in said groove, and a spiral spring for 40 detachably holding said strands to said back.
2. In a fountain brush or mop, a metal back of substantially circular shape having

a central opening and a peripheral groove, a reinforcing plate having a threaded opening in registration with said central groove and adapted to be screwed to a pipe, a plurality of strands, reinforcing means for securing the said strands together, said reinforcing means being arranged to enter said groove, and elastic means for detachably securing said strands and said reinforcing means to said back.

3. In a fountain brush or mop, a metal back of substantially circular shape having a central opening and a peripheral groove, a reinforcing plate having a threaded opening in registration with said central groove and adapted to be screwed to a pipe, a plurality of strands, reinforcing means for securing said strands together, said reinforcing means being arranged to enter said groove, and elastic means for detachably securing said strands and reinforcing means to said back, said elastic means comprising a spiral spring having a circular shape.

4. In a fountain brush or mop, a metal back of substantially circular shape having a central opening and being provided with a peripheral groove, a circular plate secured to said metal back and having an opening arranged to register with said central opening, a pipe having threads arranged to enter the opening in said plate and having an extension adapted to enter the central opening in the back, said extension being perforated to permit the outlet of water, a plurality of strands looped over a central reinforcing member, an outer reinforcing member for securing the strands in place, and an inner spiral spring for removably holding said strands in said groove.

CLAUDE FREDERICK.
